Primary Examiner — R. Johnson**CLAIM**

The ornamental design for a drum as shown and described.

DESCRIPTION

FIG. 1 is a front, perspective view of a drum showing my new design.

FIG. 2 is a front, bottom, perspective view thereof;

FIG. 3 is a rear, perspective view thereof;

FIG. 4 is a rear, bottom, perspective view thereof;

FIG. 5 is a front view thereof;

FIG. 6 is a rear view thereof;

FIG. 7 is a right side view, the left side view being a mirror image thereof;

FIG. 8 is a top view thereof; and,

FIG. 9 is a bottom view thereof.

The broken lines are for environmental purposes only and form no part of the claimed design.
